LOCK

Herman M. Gasstrom, Mount Vernon, N. Y.

Application March 13, 1935, Serial No. 10,807

5 Claims. (Cl. 292—226)

This invention relates to a lock. The object of the invention is the production of a lock for a swinging door, by which the latter is tightly clamped in place when closed.

5 The second object of the invention is the production of a lock, specially for the door of a moving vehicle like an automobile, by means of which said door is prevented rattling when closed, and specially when the vehicle is moving.

10 The third object of the invention is the production of a lock for a swinging door, by means of which the door can be opened or closed by means on its opposite sides.

15 The fourth object of the invention is the production of a lock for a swinging door which can be opened or closed by means on its opposite sides, and in which one of said means can be positioned to prevent the other means functioning.

The essential objects of the invention are attained with a lock having a lock bolt which can be swung and at the same time laterally moved when functioning with the keeper for the lock.

Fig. 1 represents an elevation of a door with its jamb and the improved lock connected thereto; Fig. 2 is a view similar to Fig. 1 viewed from the opposite direction; Fig. 3 shows an enlarged inside elevation of the lock and its appurtenances; Fig. 4 shows a section on the line 4.4 of Fig. 3; Fig. 5 is a section of Fig. 3 on the line 5.5; Fig. 6 represents a section of Fig. 4 on the line 6.6; Fig. 7 indicates a section on the line 7.7 of Fig. 3 when the door is completely closed; Fig. 8 shows a section similar to Fig. 7 before the door is completely closed; Fig. 9 indicates a section on the line 9.9 of Fig. 3; Fig. 10 represents a section of Fig. 3 on the line 10.10; Fig. 11 is a section of Fig. 3 on the line 11.11; Fig. 12 is a fragmentary portion of Fig. 3, with a modification; Fig. 13 shows a section as on the circular line 13 of Fig. 12 and Fig. 14 represents a section of Fig. 13 on the line 14.14.

In the drawings the jamb of a door is indicated at 20 having the cavity 21 with the inner face 22, the projecting portion 23 similar in shape to the keeper to be now described.

45 The triangular shaped keeper for the improved lock is indicated at 28 having the bottom face 29, the inclined upper face having the portions 30 and 31 with the locking face 32 between them, 50 and the locking seat having the vertical face 33 and the bottom face 34 at the rear end of the keeper.

The keeper 28 is fastened to the jamb 20 by the screws 38. A stop 39 is fastened to the jamb 20.

A fragmentary portion of a swinging door is indicated in its entirety by the numeral 40 and is shown with its outer face 41, the cavity 42 and the opening 43.

The housing of the lock is indicated in its entirety by the numeral 45 and is positioned within the cavity 42. The said housing comprises the main member 46, having the inner face 46a and the outer face 47a and is fastened to the door 40 by the screws 47b. The member 46 has extending from one side thereof and at right angles thereto the flange 48, which latter is fastened to the swinging end of the door by screws 49. The flange 48 has the opening 50 and the supplemental flange 51. In the main member 46 are indicated the openings 52 for the screws 47b to fasten the member 46 to the door 40. Openings 54 are also formed in the main member 46. Stop lugs 55, 56, 57, and 58 are pressed out from the member 46 and the pair of clamping lugs 59 are pressed out from the member 46.

The cover of the housing 45 comprises the main member 60, parallel to and spaced from the member 46 and has the flanges 61 and 62 extending at right angles thereto. The inner face of the member 60 is shown at 63 and the outer face is shown at 63a. Lugs 64 integral with the flanges 61 and 62 extend through the openings 54 of the main member 46. The main members 46 and 60 are clamped in operative position by the pivot bolt 68. A washer 69 is interposed between the head of the bolt 68 and the member 46 and a washer 70 is interposed between the member 60 and the nut 71 of the bolt 68.

With the main member 46 are formed the tapering cam cavities 74 having the walls 75 which are arcuate in cross section as indicated at 76, Fig. 4, and taper upwardly from their peaks 77a to their crowns as indicated at 77, Fig. 7. The peaks 77a are adjacent to one of the faces of a lock bolt to be described and the crowns 77 are distant therefrom.

The main member 60 has formed therewith oppositely positioned tapered cam cavities 84, which 45 face the cavities 74. The cavities 84 are shown with the walls 85, which are arcuate in cross section as indicated at 86, Fig. 4, and taper downwardly from their peaks 87a to their crowns as indicated at 87, Fig. 7. The peaks 87a are adjacent to the other face of the lock bolt and the crowns 87 are distant therefrom. 50

Between the main members 46 and 60 is rotatively positioned the disc shaped lock bolt 88 having the inner face 89 and the outer parallel 55

face 90. The said lock bolt 88 is supported on the pivot bolt 68 and has integral therewith the locking nose 91 having the bottom face 91a and the operating noses 92 and 93. The latter nose is shown with the heel 94. In one face of the lock bolt 88 are indicated the semi-spherical cavities 95 for supporting the balls 96, and in the other face of the lock bolt 88 are formed the semi-spherical cavities 97 for supporting the balls 98. The cavities 95 are preferably positioned between the cavities 97. The locking nose 91 is adapted to extend through the opening 50.

An operating lever 100 is indicated having the main member 101 with the flange 102 at right angles thereto at one side and the short flange 103 at its longitudinal edge 104. The member 101 of the lever 100 bears against the inner face 46a of the main member 46 of the housing 45, and the edge 104 of the lever 100 is adapted to bear against the stop lug 55. A depressed portion 106 is made in the member 101, which engages the opening 107 in the member 46. U-shaped lugs 108 extend from the depressed portion 106 and engage the perimeter of the opening 107. A square shaped opening 110 is indicated in the depressed portion 106.

An outside operating handle 114 has integral therewith the stem 115. A square shank 116 extends through the opening 43 in the door 40 and through the square opening 110. The shank 116 has integral therewith the flange collar 117 and from the latter extends the hub 118. A threaded shank 119 extends from the hub 118 and is in threaded engagement with the stem 115. A cup shaped cover bracket 120 is fastened to the member 46 over the opening 107, by means of the screws 121. A cup shaped bracket 125 bears on the outer face 41 of the door 40 and is fastened thereto by the bolts 126. The bracket 125 has formed therein the circular opening 127 which engages the hub 118.

A plate spring 130 is positioned upon the inner face of the main member 46 of the housing 45, and one side of a portion 131 of said spring bears against the flange 103, and the other side of a portion of said spring 130 bears against the stop lug 56. The said spring 130 at one end is engaged by the rivet 134 which extends through the member 46.

A spiral spring 140 having the outer flat end 141 and the inner flat end 142, bears on the inner face of the member 46 of the housing 45. The flat end 141 bears against the heel 94 of the nose 93, and the flat-end 142 is clamped between the clamping lugs 59.

A second operating lever 150 is indicated having the main member 151 with the longitudinal flange 152 at right angles thereto at one side thereof, and the end flanges 153 and 154 at one end thereof. The member 151 of the lever 150 bears against the inner face of the main member 46 of the housing 45 and one edge of the lever 150 is adapted to bear against the stop lug 57.

A depressed portion 156 is formed in the member 151 and engages an opening 157 in the member 46. From the depressed portion 156 extend the U-shaped lugs 158 that engage the perimeter of the opening 157. A square opening 160 is made in the depressed portion 156. A cup shaped bracket 165 having the circular opening 166 is fastened to the member 46 by means of the screws 167.

An inside operating handle 168 is shown with the stem 169, to which latter is connected the square shank 172, which extends through the

square opening 160. The said shank 172 which extends through the opening 160, is shown with the flange collar 174 from which extends the hub 175 and from the latter extends the threaded shank 176, which is in threaded engagement with the stem 169.

A spring 180 bears on the inner face of the member 46 and one end thereof is engaged by the rivet 181. The swinging end 182 of said spring is adapted to bear against either the flange 153 or 154. Referring to the modification indicated in Figs. 12, 13 and 14, the disc shaped lock bolt similar to 88, is indicated at 88a. Tapering projections 100 extend from one face of the bolt 88a and similar oppositely positioned tapering projections 105 extend from the opposite face of said bolt. The main member of the housing of the lock bolt similar to 46 is indicated at 46x. Tapering cavities 74a are indicated in the member 46x. The main member 20 of the cover of the housing for the lock bolt 88a is shown at 60a. Tapering cavities 84a oppositely positioned to the cavities 74a but similar thereto are indicated for the main cover 60a.

In the drawings the door 40 is indicated in its closed position with the lock bolt 88 having its outer face 90 bearing against the vertical face 33 of the locking seat of the keeper 28 as indicated in Figs. 4 and 6. In this position the outer face 47a of the main member 46 of the housing 45 abuts against the stop 39, and the door 40 is securely locked in its closed position and is prevented from rattling. The end 141 of the spiral spring 140 abuts against the heel 94 of the nose 93 of the lock bolt 88 to maintain the latter in locked position. The lock bolt 88 in this position bears against the inner face 63 of the main member 60 of the cover of the housing of the lock. The balls 96 and 98 at the closed position of the door are respectively located in their cam cavities 74 and 84 as indicated in Fig. 7, that is to say, the balls 96 are at the peaks 77a, and the balls 98 are at the crowns 87.

If the lock is to be opened from the outside, the second operating lever 150 must be positioned in its lowered position as indicated in full lines in Fig. 3, and the operating handle 114 is turned in the direction of the arrow A, Fig. 1, and thereby the operating lever 100 is swung in the same direction as indicated by the arrow A, Fig. 3.

The flange 102 of the operating lever 100 will bear against the nose 92 of the lock bolt 88 and the latter will be turned in the direction of the arrow C, Fig. 3, and the locking nose 91 of the lock bolt 88 rises out of contact with the face 33 of the keeper 28. The direction of the movement of the lock bolt 88 in Fig. 7 is indicated by the arrow D. At the same time the balls 98 move from the crowns 87 of the cam cavities 84 to the peaks 77a, and the balls 96 move from the peaks 77a to the crowns 77 of the cam cavities 74 as indicated in Fig. 8. By the coaction of the balls 98 with the cam cavities 84, as just described, the lock bolt 88 as it swings in the direction of the arrow C, Fig. 3 moves laterally 65 in the direction of the arrow E, see Fig. 4, and the door 40 can be easily swung open as indicated by the arrow O, Fig. 4.

When the door 40 is in its closed position the nose 92 bears against the flange 102 of the lever 100 and the longitudinal edge 104 of said lever bears against the stop lug 55 and the flange 103 bears against the portion 131 of the spring 130. At the same time the flange 152 of the lever 150 bears against the nose 93. The spring 130 main- 75

tains the operating lever 100 in its raised position when not actuated by the operating handle.

If the second operating lever 150 is located in the position indicated in the dotted lines in Fig. 3, the door can not be swung open from the outside by means of the operating handle 114.

After the door is open the tension of the spring 140 automatically locates the lock bolt 88 in the position indicated in Fig. 3. When the door is 10 swung to its closed position without the use of the operating handle the lock bolt 88 approaches the keeper 28, the bottom face 91a of the nose 91 slides up the inclined face 30 and then drops to the inclined face 31 and slides up the latter until seated in the seat having the faces 33 and 34. When the lock bolt 88 is being seated as just described, it swings in a direction opposite to the arrow C, Fig. 3 and opposite to the arrow D, Fig. 7. By the coaction of the balls 96 20 with the cam cavities 74 the said balls 96 move from the crowns 77 to the peaks 77a and the door moves laterally in the direction of the arrow E, by virtue of which the door 40 is positioned with the outer face 47a of the member 46 bearing 25 against the stop 39. The door may also be closed by using the operating handle 114 or 168.

If the door is in its closed position as indicated in Fig. 4 and it is to be swung open from the inside, the operating handle 168 is swung 30 in the direction of the arrow M, Fig. 2, to swing the operating lever 150 in the direction of the arrow M, Fig. 3, by reason of which the longitudinal flange 152 bears against the nose 93 of the lock bolt 88 and the latter turns in the direction of the arrow C, Fig. 3, as already described and the balls 96 and 98 will be positioned with respect to their cam cavities as shown in Fig. 7 as already described and the lock bolt 88 will move in the direction of the arrow E, Figs. 4 and 40 6, as described, and will leave the keeper 28 of the lock as described. While the operating lever 150 is swung in the direction of the arrow M the flange 153 is bearing against the end 182 of the spring 180.

45 It will be noted that the lock bolt 88 can be positioned with its locking nose in engagement with the locking face 32 of the keeper 28, and in such a case the door 40 will be positioned partly open.

50 Attention is called to the fact that the mechanism of this invention and especially the means of moving the lock bolt laterally can be applied to a latch. With the modification indicated in Figs. 12, 13, and 14, the lock bolt 88a is moved 55 laterally by the coaction of the projection 100 with the cavities 74a, and the coaction of projections 105 with the cavities 84a.

The door 40 may be constructed in various ways and in swinging connection with a stationary structure or with a moving vehicle.

Various modifications may be made in the invention and the present exemplifications thereof are to be considered illustrative and not limitative thereof.

65 Having described my invention, I claim:

1. In a mechanism the combination of a housing, members of the housing spaced from each

other, cam cavities in each of said members, a lock bolt pivoted in said housing between its members, means to swing the lock bolt in opposite directions, means in the opposite faces of the lock bolt, the latter means coacting with their adjacent cam cavities to laterally move the lock bolt in opposite directions as said lock bolt is 5 swung in opposite directions.

2. In a lock the combination of a housing, members of the housing parallel to each other 10 and spaced from each other, tapering cam cavities in each of said members, the cavities in one member oppositely positioned to the cavities of the other member, a lock bolt pivoted to said housing between its members, means to swing the 15 lock bolt in opposite directions, balls supported in cavities in the opposite faces of the lock bolt, said balls coacting with their adjacent cam cavities to laterally move the lock bolt in opposite directions as said lock bolt is 20 swung in opposite directions.

3. In a lock the combination of a housing, members of the housing parallel to and spaced from each other, tapering cam cavities in each of said members, the cavities in one member 25 oppositely positioned to the cavities of the other member, each of said cavities comprising a wall arcuate in cross section having a peak at one end and leading to a crown at its other end, a lock bolt having parallel faces pivoted to said housing between said members, said lock bolt having semi-spherical cavities in its faces, and a ball supported in each of said cavities of the lock bolt, said balls each coacting with one of their adjacent cam cavities to laterally move the lock 30 bolt in opposite directions as said lock bolt is 35 swung in opposite directions.

4. In a lock the combination of a housing, members for the housing parallel to each other and spaced from each other, tapering cam cavities in each of said members, the cavities in one member oppositely positioned to the cavities of the other member, a lock bolt pivoted to the housing between its members, means to swing the lock bolt in opposite directions, tapering projections extending from the opposite faces of the lock bolt, said projections coacting with their adjacent cam cavities in the members of said housing to laterally move the lock bolt in opposite directions as said lock bolt is 40 45 swung in opposite directions.

5. In a lock the combination of a housing, said housing comprising a main member and a cover parallel thereto constituting the second member, each of said members having cam cavities, a lock bolt pivoted in said housing between its members, a pair of operating noses integral with the bolt, a heel integral with the bolt, means coacting with the operating noses to swing the bolt in the same direction, means coacting with the heel to swing the bolt in the opposite direction and means for the bolt coacting with the cam cavities of the members of the housing to laterally move the bolt in opposite directions as it swings in opposite directions. 55 60 65

HERMAN M. GASSTROM.
